United States Patent Office

Des. 216,377
Patented Dec. 23, 1969

216,377

PHOTOCOMPOSING MACHINE

Wesley W. Miller, Wyncote, Pa., Hugh T. Greenlee, Gates Mills, Ohio, and Charles D. Hagerty, Philadelphia, and Gerold Litschi, Lansdale, Pa., assignors, by mesne assignments, to W. R. Grace & Co., New York, N.Y., a corporation of Connecticut

Filed Jan. 13, 1969, Ser. No. 15,319

Term of patent 14 years

Int. Cl. D16—99

U.S. Cl. D61—1

FIG. 1

FIG. 2

FIG. 3

FIG. 4

FIG. 1 is a perspective view of a photocomposing machine embodying our new design,

FIG. 2 is a front elevational view thereof,

FIG. 3 is a left-side elevational view thereof, and

FIG. 4 is a top elevational view thereof.

FIGURES 1 and 4 show a grill-like surface pattern on the upper surface of the machine within the line boundaries.

We claim:

The ornamental design for a photocomposing machine, as shown and described.
